US00D823284S

(12) **United States Design Patent** (10) **Patent No.:** **US D823,284 S**
Zhang et al. (45) **Date of Patent:** **** Jul. 17, 2018**

(54) **POLARIZED ANTENNA**

(71) Applicants: **Aerohive Networks, Inc.**, Milpitas, CA (US); **Wistron NeWeb Corporation**, Hsinchu (TW)

(72) Inventors: **Liangfu Zhang**, Hangzhou (CN); **George Gang Chen**, Fremont, CA (US); **Changming Liu**, Cupertino, CA (US); **Zhenye Cao**, Hangzhou (CN); **Shang-Sian You**, Hsinchu (TW); **Yu Tao**, Hsinchu (TW); **Chi-Kang Su**, Hsinchu (TW)

(73) Assignees: **Aerohive Networks, Inc.**, Milpitas, CA (US); **Wistron NeWeb Corporation**, Hsinchu (TW)

(**) Term: **15 Years**

(21) Appl. No.: **29/538,311**

(22) Filed: **Sep. 2, 2015**

(51) LOC (11) Cl. **14-03**

(52) U.S. Cl.

USPC **D14/230**
